Primary Examiner — Ryan Harvey(74) *Attorney, Agent, or Firm* — Neal, Gerber & Eisenberg LLP(57) **CLAIM**

The ornamental design for a betting terminal, as shown and described herein.

DESCRIPTION

FIG. 1 is a first front perspective view of a betting terminal of our new design.

FIG. 2 is a second front perspective view of the betting terminal of FIG. 1.

FIG. 3 is a front view of the betting terminal of FIG. 1.

FIG. 4 is a rear view of the betting terminal of FIG. 1.

FIG. 5 is a left side view of the betting terminal of FIG. 1.

FIG. 6 is a right side view of the betting terminal of FIG. 1.

FIG. 7 is a top view of the betting terminal of FIG. 1; and,

FIG. 8 is a bottom view of the betting terminal of FIG. 1.

The portions shown in phantom are not part of the claimed design.
